UNITED STATES PATENT OFFICE.

JOHN PAUL HASS, OF INTERNATIONAL FALLS, MINNESOTA.

WHITE-WATER SELF-CLEANING SETTLING TANK.

Application filed December 21, 1925. Serial No. 76,855.

This invention relates to improvements in pulp recovery devices for use in connection with paper making, having for an object to provide an advantageous form of settling tank for the so-termed "white water" resulting or occurring during the making of paper from pulp, the tank being of such construction that the particles of pulp in the "white water" will be effectually removed therefrom prior to its discharge into waste, hence, effecting a material saving upon part of a manufacturer.

It is likewise an equally important object of the invention to provide a device of the character described in which "white water" is discharged whereby the pulp content thereof will be effectually and economically removed by settling to the bottom of the tank, whereupon such stock will be immediately and fully removed from the tank, hence preventing its fermentation and avoiding the floating of the pulp with its resultant loss in the overflowing waste or sewerage "white water".

Yet another and equally important object of the invention is to provide the settling tank with means movable along and over the bottom thereof for effectually engaging and removing the settled pulp from the tank bottom and directing it into a discharge means in order that the same will be conveyed from the tank and prevented from accumulating therein.

Other objects of the invention will be in part obvious, and in part pointed out hereinafter.

In order that the invention and its mode of operation may be readily understood by persons skilled in the art, I have in the accompanying illustrative drawings, and in the detailed following description based thereon, set out one embodiment of the same.

In these drawings:—

Figure 1 is a plan view of the improved settling tank having parts thereof broken away;

Figure 2 is a vertical longitudinal fragmentary section through the same;

Figure 3 is a fragmentary detail in vertical transverse section taken on a line 3—3 of Figure 2 looking in the direction in which the arrows point, and

Figure 4 is a fragmentary detail, in longitudinal section showing the mounting of the scraper bars upon the endless chain and

their engagement with respect to the tank bottom.

Having more particular reference to the drawings, in connection with which like characters of reference will designate corresponding parts throughout, the improved settling tank may be stated to comprise a receptacle generally indicated herein by the numeral 1, such receptacle being shown in this embodiment to be of substantially rectangular formation and provided with a rearwardly inclined bottom 2, while "white water" inlet feed pipes 3 are connected with the upper portion of the forward end thereof and are adapted to discharge into a head box 4 whereby the same may pass or flow over an overflow wall 5 into the tank proper in the manner clearly indicated in Figure 2; a perforated stilling box or a trough 6 being arranged in fixed relation to the upper portion and inner side of the wall 5 whereby to receive the flow of "white water" from the head box 4 over the marginal portion of said overflow wall 5. A waste discharge box 7 is fixedly arranged with respect to the outer side and upper end of the rearward wall 8 of the tank 1 and as will be noted, has an outlet trough 7' extended laterally therefrom into communication with any suitable sewerage system, not shown herein, in order that the waste water may be effectually conveyed from the settling tank. At this point, it is to be also noted that communication of the tank proper with the discharge box 7 is effected over an overflow wall 9 upon the upper portion of the rearward end wall 8 and by consequence, when the level of "white water" in the tank reaches a height as indicated in Figure 2, there will be a continual flow of the waste water into the discharge box 7 for discharge from the settling tank.

As means for conducting clear "white water" from the settling tank for washing and other purposes, an overflow or outlet pipe 10 communicates with an upper portion of the rearward end of one side wall of the receptacle 1, in a manner indicated in Figure 2, thus allowing such clear "white water" to be conducted from the tank, this clear "white water" of course resulting from the settling of the pulp therefrom onto the inclined bottom 2.

To prevent surging or similar undesirable agitation of the "white water" if any, in the

tank 1 and to expedite the settling of pulp therefrom onto the inclined bottom 2, I may and preferably do mount a rearwardly inclined transversely positioned baffle 11 there-in, securing the opposite ends of such baffle in a suitable manner to adjacent portions of the opposite side walls of the tank 1; the lower and rearwardly disposed portion of such baffle 11 being arranged in spaced relation with respect to the inclined bottom 2.

With a view towards providing the rearwardly inclined bottom 2 of the settling tank 1 with means for effectually and positively removing the settled pulp from such bottom and from the tank whereby to avoid its accumulation and resultant fermentation with flotation of particles of the pulp upon the waste or "white water", an endless and longitudinally moving scraping or raking device is employed, the same preferably consisting of relatively parallel transversely disposed shafts 12 and 13 journaled in suitable bearings adjacent the inner side or faces of the opposite side wall of the receptacle 1 and fixedly carrying sprocket wheels 14 upon the opposite extremities thereof, as well as upon the intermediate portions of the same in a manner clearly shown in Figure 3; a longitudinally disposed rib 15 being fixedly arranged upon the intermediate portion of the inclined bottom 2 and extended longitudinally throughout the greater portion of its length. Endless sprocket chains 16 are engaged about and movable over the various pairs of sprocket wheels 14 mounted upon the several shafts 12 and 13 and carry thereon, pivotal scraping or raking bars 17, said bars 17 being disposed transversely of the bottom 2 of the tank 1 and positioned in those ways provided between the opposite side walls of said tank and the opposite sides of the longitudinally disposed intermediate-ly placed rib 15. To effectively support the endless sprocket chains 16 throughout their respective lengths during longitudinal movement through the settling tank 1 and to insure proper engagement of the various arms 17 with the inclined bottom 2 at appropriate times, tracks 18 preferably formed of angle iron are secured to the lower portions of the inner sides of the opposite side walls of the tank 1 in parallel relation to the rearwardly inclined bottom 2 and to the upper portions of the opposite sides of the longitudinally disposed intermediately spaced rib 15, these tracks 18 being adapted to receive and to movably support the lower or under sides of the endless sprocket chains 16. The upper sides or portions of the sprocket chains 16 are adapted to be movably supported upon other and similar longitudinally disposed pair of tracks 19, the same being likewise formed of angle iron and hav-ing fixed or immovable support with respect

to the settling tank 1 through the medium of a plurality of equi-spaced transversely disposed I-beams 20, the opposite ends of which are suitably anchored to adjacent portions of the inner sides of the opposite side walls 70 of said tank 1. In this connection, it is to be noted that the upper pairs of longitudinally disposed tracks 19 are also arranged in parallelism with the rearwardly inclined bottom 2, while the opposite extremities 75 thereof are bent or curved downwardly as indicated at 21. Likewise, the lower portions of said pairs of tracks 19 are of widths greater than the corresponding portions of the pairs of tracks 18 and consequently upon 80 this, it will be appreciated that with longitudinal movement of the endless sprocket chains 16, the pivotally mounted bars 17 when moving in proximity to the rearwardly inclined bottom 2 will be permitted to 85 swing by gravity to those downward positions as shown in Figures 2 and 3 thus effecting a scraping or raking engagement with the surface of said bottom 2. However, as the longitudinal movement of the 90 sprocket chains 16 over their respective sprocket wheels 14 continues, the pivotally mounted bars 17 will be moved between the upper sets of tracks 19 and because of the fact that the lower portions of these 95 tracks are of greater widths than the corre-with said bottoms of the tracks 19 and will be understood that the extremities of said pivotally mounted bars 17 will be engaged with said bottoms of the tracks 19 and will 100 be moved to feathering positions with respect to the pulp and "white water" in the settling tank, in the manner clearly indicated in Figure 4. In this way it will be appreciated that the inner or upper bars 105 17 will be prevented from effecting undul-and undesirable agitation of the "white water" in the settling tank and hence, that the settling of pulp or stock therefrom onto the inclined bottom 2 will be materially ex- 110 pedited. As the various bars 17 become disengaged from the opposite or forwardly disposed ends of the said upper tracks 19 it is manifest that they will freely swing by 115 gravity and therefore during their sequen-tial passage over the inclined bottom 2, will move into raking engagement with the sur-face thereof in the manner as is also illus-trated in Figure 4. Thus, it will be under- 120 stood that the pulp or stock settling onto the inclined bottom 2 will be engaged by the scraping bars 17 and will be moved longitudinally over the rearward ends of the tank 1.

In order that the settled pulp or stock 125 engaged and moved longitudinally and rear-wardly over the inclined bottom 2 may be conducted from the settling tank, a trans-versely disposed trough 2 is formed in the rearward end of the settling tank 1 below 130

the surface of the rearward end of the inclined bottom 2 and has a spiral conveyor 23 mounted therein, the carrying shaft of which is journaled in suitable bearings in 5 adjacent portions of the side walls of said receptacle. One end of this carrying trough, indicated for the purpose of convenience by the numeral 24, is extended beyond one side wall for a purpose which will be presently 10 described.

To provide this scraping device and the spiral conveyor with drive means, a housing 25 is arranged adjacent the rearward portion of one side wall of the settling tank, in 15 the manner indicated in Figure 1, said housing receiving therein the extended end of a conveyor carrying shaft 24 together with the laterally extended end of the shaft 13; the extended end of the shaft 24 passing through 20 a sleeve-like extension 26 suitably supported within the housing 25 and having communication through an elbow 27 with a stock moving pump 28, said pump being operated from an electrical motor 29 or similar actuating 25 means and having the discharge conduit 30 thereof connected to and communicating with a discharge pipe 31, adapted to discharge the recovered or settled pulp or stock into suitable or appropriate apparatus in the 30 mill equipped with the improved settling tank.

A pulley wheel is mounted upon the extended end of the conveyor carrying shaft 24 and has a belt or other suitable motion 35 transmitting device 32 engaged thereover, this device passing over a similar pulley wheel mounted upon a driving shaft 33 adapted to receive its drive or rotary motion through the medium of suitable gearing 34 40 from a motor or other source 35 mounted in the housing 25. Also, the extended end of the shaft 13 carries a pulley wheel thereupon about which an endless belt or similar motion transmitting device 36 is engaged, 45 the latter in turn engaging about a second pulley wheel mounted upon the driving shaft 33 in order that rotary motion may be also transmitted to said shaft 13, effecting its rotation and the consequent transmission of 50 longitudinal movement to the endless sprocket chains 16 carrying the pivotally mounted bars 17 in order that the latter may be moved longitudinally through the settling tank 1 and over the upper surface of 55 the rearwardly inclined bottom 2 of said settling tank to effectively remove the settled and accumulated pulp or stock therefrom to the transversely disposed trough 22.

The operation of the settling tank may be 60 reviewed as follows:—

“White water” is discharged into the settling tank 1, reaching the level as indicated in Figure 1 of the drawing, said “white water” flowing over the upper marginal portion of the overflow wall 5 from the said 65 box 4 into the receptacle proper, by way of the stilling box 6, surging or similar undue agitation of said “white water” within the tank proper being prevented by the arrangement of the transversely positioned baffle 11. 70 The pulp or stock contained in the “white water” will settle onto the rearwardly inclined bottom 2 of the tank whereupon it is immediately engaged by the rearwardly and longitudinally moving lowermost bars 17 and 75 directed over the rearwardly inclined bottom 2 into the transverse trough 22 whereat the spiral conveyor 23 will function to discharge the same laterally to the outlet port in the side wall adjacent one end of said spiral 80 conveyor into the sleeve 26, following which the stock pump 28 will serve to move it along and discharge it, under pressure, into the conduit 31 for conveyance to the mill. 85 Due to the fact that the uppermost pivotal bars 17 move to feathering positions when engaged with the oppositely disposed pairs of tracks 19 it will be understood that excessive agitation of the “white water” within 90 the tank will be avoided.

Manifestly, the construction shown is capable of considerable modification and such modification as within the scope of the appended claims, I consider within the spirit 95 of my invention.

I claim:

1. In combination, a tank having a head box, a perforated trough, and an overflow wall between the box and trough whereby a fluid from said box will pass over said wall 100 and drop into said trough, a baffle inclining from a point adjacent said trough toward the bottom of said tank and an endless scraping device having its head portion arranged under said trough and said inclined baffle. 105

2. In combination, a tank having a head box, a perforated trough, and an overflow wall between the box and trough whereby a fluid from said box will pass over said wall 110 and drop into said trough, a baffle inclining from a point adjacent said trough toward the bottom of said tank, an endless scraping device having its head portion arranged under said trough and said inclined baffle, and a combined spiral conveyor and suction device 115 arranged directly below the discharge end of said scraping device.

In witness whereof I have hereunto set my

J. PAUL HASS.
